UNITED STATES PATENT OFFICE

152,459

DESIGN FOR A BOOKSTALL

James Stott Dawson, New York, N. Y.

Application July 27, 1946, Serial No. 132,039

Term of patent 7 years

(Cl. D80—9)

To all whom it may concern:

Be it known that I, James Stott Dawson, a subject of the King of Great Britain, residing at New York, in the county of New York and State of New York, have invented a new, original, and ornamental Design for Bookstalls, of which the following is a specification, reference being had to the accompanying drawings, forming part thereof.

In said drawings:

Figure 1 is a perspective view of the front of a bookstall, showing my new design;

Figure 2 is a perspective view of the bookstall, looking at it from the rear of the bookstand portion at the left of Figure 1; and

Figure 3 is a reduced-scale top plan view, partly in section along the line 3—3 of Figure 1.

I claim:

The ornamental design for a bookstall, substantially as shown.

JAMES STOTT DAWSON.
